Patented Aug. 29, 1922.

UNITED STATES PATENT OFFICE.

GERHARD RIESNER, OF MELROSE, MINNESOTA.

STEERING MECHANISM.

1,427,641.

Specification of Letters Patent. Patented Aug. 29, 1922.

Application filed June 23, 1921. Serial No. 479,865.

To all whom it may concern:

Be it known that I, GERHARD RIESNER, a citizen of the United States, residing at Melrose, in the county of Stearns and State of Minnesota, have invented certain new and useful Improvements in Steering Mechanism, of which the following is a specification.

This invention relates to steering devices and more particularly to that class of structures attached to the tongue of a drawn machine or apparatus, such as a threshing machine for instance, whereby the same may be easily and quickly directed to follow the tractor or propelling machine.

The primary object of the invention resides in the construction of a manually operable steering mechanism designed particularly for attachment to the tongue of a threshing machine or the like, whereby the drawn machine may be quickly and easily turned to the left or right and turn sharp corners to properly follow in the path of the propelling machine without stopping the same and in addition permit the backing or pushing of the threshing machine in between stacks of grain in places where it is not possible or impracticable to draw the machine.

Another object of the invention is the construction and arrangement of a novel and improved manually operable steering mechanism capable of being attached to the tongue of various types of drawn machines such as threshing machines, and the like, and one which is totally devoid of gearing, and affording a wide range of leverage for operating the device from different positions on the drawn machine.

A still further object of the invention is to provide a steering apparatus capable of being installed and attached without considerable labor or skill to the tongue of a drawn machine, and one in which the parts are extremely simple in construction easily assembled, rigid and durable, highly efficient in operation, practical and capable of being manufactured at a very low cost whereby its commercial possibilities are greatly enhanced.

With these objects in view and others which will be manifest and suggested as the purpose and nature of my invention are revealed in the following specification and drawing wherein I have shown a preferred embodiment thereof,

Figure 1 is a plan view of the device, Fig. 2 is a side view thereof, Fig. 3 is a front view in section on the line 3—3 of Fig. 1, and, Fig. 4 is a detached perspective view of the lever guide.

Referring now to the drawings, wherein like numerals designate corresponding parts throughout the several views, 5 designates the front axle of a propelled machine such as a thresher.

The improved device which is the subject matter of the present application comprises a tongue member 6 which is substituted for the usual draft tongue of the thresher or other machine to be drawn.

Extending transversely of the tongue member 6 and in parallel relation to an axle 5, the latter representing the forward axle 75 of the machine to be drawn, for instance a threshing machine, not shown, is a hood member 9 coupled by eye-bolts 7 and 8 to the axle. Extending from the member 9 are obliquely directed members 15 and 16, and bearing upon the upper and lower faces of the member 9 are straps 19 having forward extension portions 20 to bear upon the upper and lower faces of the obliquely directed members 15 and 16, the four portions being secured together by rivets, as shown.

At their forward ends the members 15 and 16 are coupled by curved or segmental straps 17 with their ends 18 directed rearwardly to engage the upper and lower faces of the members 15 and 16, and connected thereto by rivets, as shown. The upper face of the tongue 6 is provided with a strap 24, while another strap 10 bears upon the lower face of the tongue and in advance of its forward end as shown at 11. At their rear ends the straps 10 and 24 extend over the member 9 and its straps 19 and are pivotally united to the latter at 25.

The tongue extends between the segmental members 17 and is free to swing laterally on the pivot 25.

Supporting braces 21 are connected at one end to the member 9, preferably by the stocks of the eye-bolts 7, and bent at the other end as shown at 22 and connected to the forward ends of the members 15 and 16.

Pivoted at 26 to the strap 24 is a lever member 27 having lateral extensions 28 at its forward end as shown in Fig. 4, and with a hood or guard 27' at the pivoted end.

Bearing over the head member 28 is a

strap 39 having an upwardly arching keeper 39. Pivoted at 35 between the members 28 and 39 are link devices 30 and 31 with the outer ends of the links pivoted at 32 respectively to the curved strap members 17.

Extending loosely through the keeper 33 and into the housing 27 is a lever member 29 and preferably loosely engaged by the pivot 26. The keeper 33 is of sufficient height to permit the lever member 29 a certain degree of vertical movement, the object to be hereafter explained.

The members 17 are provided with apertures to receive a holding pin 36 to be inserted when the tongue is to be held rigidly in a central position, or when the thresher or other vehicle is being drawn straight ahead. The pins 36 prevent the side movement of the steering mechanism, but when once removed upon operating the lever 29 to the left or right, the entire frame work or quadrant above referred to may be turned with respect to the tongue 6, and since the loose connection between the machine and the propelled tractor machine permits the same to be turned to the right or left, the action being easily accomplished by operating the lever 29 in the manner above set forth. The lever 29 may be of any length desired, but will be as long as convenient as the greater the leverage the easier the operation. The frame work of the mechanism proper is so reenforced by the top and bottom plates 10 and 24 that all danger of the same being broken is eliminated, and since the same may be constructed of wood if so desired, the device may be cheaply manufactured and installed without considerable skill or labor on various types of machines, since all gearing has been dispensed with.

In the accompanying drawings, I have illustrated my invention embodied in one form by way of example, and which in practice has been found to be highly satisfactory in obtaining the desired results. It will be obvious however that other embodiments may be adopted and that various changes in the details of construction may be resorted to by those skilled in the art without departing from the spirit and scope of the invention. It is furthermore understood that the invention is not necessarily limited or restricted to the precise elements shown except in so far as such limitations

are specified in the subject matter being claimed.

Having shown and described the invention, what I now claim as new and desire to secure by Letters Patent of the U. S. is:—

1. In a device of the class described, a transverse head member adapted to be coupled to the machine to be moved and having diverging side members, segmental plates in spaced relation and connected to the free ends of said diverging members, a draft tongue pivotally coupled to said transverse member and extending between said spaced segmental plates and movable laterally between the same, a lever member pivoted at one end relative to said tongue, a keeper device loosely engaged by said lever member, and links connected respectively to said keeper device and to said diverging members.

2. In a device of the class described, a transverse head member adapted to be coupled to the machine to be moved and having diverging side members, segmental plates in spaced relation and connected to the free ends of said diverging members, a draft tongue pivotally coupled to said transverse member and extending between said spaced segmental plates and movable laterally between the same, a bar pivoted at one end to the tongue and having laterally directed projections at the free end, a keeper device attached to said projections and including an upwardly directed guide portion, an operating lever pivoted at one end to said bar and extending loosely through said keeper, and links connected respectively to said keeper device and to said diverging members.

3. In a device of the class described, a transverse head member adapted to be coupled to the machine to be moved and having diverging side members, a guide device connected to the free end of said diverging head members, a draft tongue pivotally coupled to said transverse members and movable laterally relative to said guide device, a lever member pivoted at one end relative to said tongue, a keeper device loosely engaged by said lever member, and links connected respectively to said keeper and to said diverging members.

In testimony whereof, I affix my signature hereto.

GERHARD RIESNER.
